UNITED STATES PATENT OFFICE.

CHESTER S. JENNINGS, OF WELLESLEY FARMS, AND CLIFFORD R. DUMBLE, OF ARLINGTON, MASSACHUSETTS, ASSIGNORS TO THE LAMSON COMPANY, OF BOSTON, MASSACHUSETTS, A CORPORATION OF MASSACHUSETTS.

POWER-CONTROL APPARATUS FOR PNEUMATIC-DISPATCH SYSTEMS.

Application filed August 12, 1922. Serial No. 581,364.

To all whom it may concern:

Be it known that we, CHESTER S JENNINGS and CLIFFORD R. DUMBLE, both citizens of the United States of America, and residents of Wellesley Farms and Arlington, respectively, in the counties of Norfolk and Middlesex, respectively, and State of Massachusetts, respectively, have invented new and useful Improvements in Power-Control Apparatus for Pneumatic-Dispatch Systems, of which the following is a specification.

This invention pertains to power control apparatus for pneumatic carrier dispatch systems and has special reference to power control devices whose operation is automatically initiated by the introduction of a carrier into the transmission tube and an instance of which is disclosed in the patent to Libby, 968,576, August 30, 1910. While the device of this patent appears to be correct in principle, it is of somewhat complex design and requires considerable space for its proper installation. Other arrangements have from time to time been devised with the same general object in view as that disclosed in said patent, but all of such devices known to us consume an excessive amount of power in their operation. Previous arrangements have usually been so designed that the controlling valve is opened upon every introduction of a carrier into the transmission tube, either by the use of electrical, mechanical or pneumatic devices, and in such arrangements the valve remains open so long as the carrier is in the tube. An excessive amount of air is thus used, as it is manifest that the blast of air produced in the transmission tube upon the introduction of a single carrier would be capable of moving several carriers as readily as one, and that when the carrier or carriers have acquired full velocity a much less quantity of air is required to carry them to their destination, than is necessary at the start. In fact in many instances the admission of air might well cease entirely prior to the discharge of the carrier from the transmission tube, while on the other hand, if the carrier emerge while under the full air pressure it is violently expelled from the tube together with a powerful blast of air,

causing annoyance and possible injury to the attendant and subjecting the carrier to unnecessary wear.

Principal objects of the invention are to provide a power regulator by means of which the controlling valve will be widely opened, upon the introduction of a carrier into the tube, but which will permit the valve to close after a predetermined interval regardless of the presence of a carrier in the transmission tube and which will only open again upon a substantial decrease in pressure in the tube due to the continued presence of the same carrier therein or the introduction of a second carrier after the discharge of the first; to provide a power regulator which will be sensitively responsive to variation in pressure in the transmission tube; certain in action under substantially all ordinary circumstances of commercial use; and of simple and compact construction requiring but little space for its installation.

In the accompanying drawings one desirable embodiment of the invention is illustrated by way of example, and in such drawings:

Fig. 1 is a fragmentary, diagrammatic side elevation of a portion of a pneumatic dispatch tube system showing the present controlling device as applied thereto;

Fig. 2 is a vertical, diametral cross section of the controlling device forming the immediate subject matter of the present invention, drawn to much larger scale;

Fig. 3 is a fragmentary detail view of a portion of the mechanism illustrated in Fig. 2, showing the parts in a different position; and

Fig. 4 is a view similar to Fig. 3 but illustrating a slight modification.

Referring to Fig. 1, the numeral 1 indicates a portion of the central station desk of a carrier dispatch system, while 2 designates one of the several carrier transmission tubes extending from the various sub-stations, and provided at the central station desk with the discharge terminal 3 normally closed by a valve 4 all in usual manner. The transmission tube 2 is continued as indicated at 5 beyond the discharge terminal and ends in a substantially horizontal por-

tion 6 forming part of the casing of the controlling device hereinafter more fully described. The usual vacuum drum is indicated at 8. One end of the section tube 9 is connected to this drum, the other end of the tube extending in a substantially horizontal plane and terminating in the part 10 also forming a portion of the casing of the controlling apparatus. The terminal portion 6 of the transmission tube and the terminal portion 10 of the suction tube are preferably arranged substantially in alignment as indicated in Fig. 2.

The casing of the controlling apparatus is provided with a chamber 11 which communicates with the end 6 of the transmission tube and with a chamber 12 communicating with the suction tube, these chambers being separated by means of a transverse partition 13 extending across the casing. This partition is provided with an opening 14 of substantial area to provide communication between the chambers 11 and 12, this opening being defined by an annular valve seat 15. A main disc valve 16 co-operates with the valve seat, being carried by a stem 17 which slides in a bore in a sleeve member 18 supported centrally of the opening 14 by means of arms such as 19. The upper or rear wall of the chamber 12 is defined by a flexible diaphragm 20. The edges of this diaphragm are clamped between a flange 21 carried by the main part of the casing and a flange 22 forming the edge of a secondary portion 23 of the casing. The space to the rear of the diaphragm 20 constitutes a chamber 24 which is normally closed against the entrance of atmospheric air.

40 The central part of the diaphragm is clamped between rear and front plates or washers 25, 26 respectively, which are secured to the end of the valve stem 17 by means of a nut 27. A spiral spring 28 is interposed between the washer 26 and the arms 19 which support the sleeve 18 and tends normally to hold the diaphragm in the position shown in Fig. 2 and at the same time to hold the valve disc 16 against its seat 15. The stem 17 is provided with an axial passage 29 which opens at one end into chamber 24 behind the diaphragm 20 and whose other end opens as indicated at 31 through the side wall of the stem 17. 45 The opening at 31, when the parts are arranged as shown in Fig. 2 lies slightly to the rear of the end wall 32 of the sleeve 18 thus providing a passage of small capacity for the flow of air from the chamber 24 to the chamber 12, but when the valve 16 is fully open, the orifice at 31 is covered by the sleeve 18 thus closing the passage 29. A restricted by-pass opening comprising the ports 33, 34 is also provided for permitting 50 air to pass from the chamber 24 to the cham-

ber 12, being regulated by means of a needle valve 35 controlled by a handle 36. The partition 13 between the chambers 11, 12 is also furnished with a constantly open passage 37.

The secondary part 23 of the casing is furnished with the outwardly flaring walls 38 having openings 39 therein and terminating in a flange 40. The edges of a diaphragm 41 are clamped between the flange 40 and the flange 42 of the cover member 43 of the casing, this diaphragm 41 forming the bottom wall of a chamber 44 within the cover member. The cover member 43 is furnished with a lateral extension 45 providing a passage 46 which communicates with one end of a pipe or tube 47 whose other end extends through the side wall of the tube 6 and is bent as indicated at 48 at substantially right angles to the main part thereof so that its opening is directed oppositely to the flow of air in the tube 6, the direction of which is indicated by the arrow 49. The cover member 43 is provided with a boss 50 having a screw-threaded bore 51 axially aligned with the valve stem 17, and with which a screw 52 engages. This screw is provided with a knurled head 53 for turning it, and has an axial bore within which a stem 54 slides freely. The central part of the diaphragm 41 is clamped between a pair of plates or washers 55, 56 respectively which are secured to the end of the stem 54 by means of a nut 57, and a spring 58 surrounds the stem 54, bearing at one end against the plate 55 and at its other against the inner end of the screw 52. This spring normally tends to hold the diaphragm 41 in the position shown in Fig. 2, the tension of the spring being variable by means of the screw 52.

The secondary member 23 of the casing is provided with an opening 59 for admitting air into the chamber 24. This opening is normally closed by means of an auxiliary governing or regulating valve 60 having an arm 61 pivoted at 62 between a pair of lugs or ears such as 63 projecting upwardly from the top member 64 of the part 23. A latch member 66 is pivoted upon a pin 67 secured to the lever arm 61 and a spring 68 surrounding such pin tends normally to swing the latch 66 in a clockwise direction as viewed in Fig. 3. The latch is provided with a toe 69 engageable with a stop pin 70 for limiting the turning of the latch.

The stem 54 extends through the diaphragm 41 and is provided with an enlarged head comprising one or more flanges of truncated conical form, three of such flanges 71, 72, 73 respectively being shown in Figs. 2 and 3. Each flange is provided with the conically inclined peripheral surface 74 and with an abrupt radial shoulder 75. The latch 66 is provided with a shoulder 76 en-

gageable with either of the radial abutment shoulders 75 and with a cam fame 77 engageable with either of the inclined faces 74. In the normal position of the parts the 5 latch is spaced from the upper shoulder 75 as shown in Fig. 2, thus permitting slight movement of the diaphragm 41 to take place without affecting the position of the valve 60.

10 In Fig. 4 a slight modification is illustrated in which the stem 54^a is furnished with but a single head or flange 71^a having the inclined surface 74^a and the radial shoulder 75^a. The valve lever 61^a is also 15 shown as supplied with a latch lever 66^a in the same manner as previously described.

In the operation of the pneumatic dispatch system herein disclosed the parts of the controlling device normally occupy the 20 position shown in Fig. 2. As a partial vacuum is maintained in the drum 8 the pressure in chamber 12 is somewhat below atmospheric pressure and thus a small quantity of air is caused to flow from the 25 chamber 11 through the passage 37, this air being drawn through the transmission tube 2. When a carrier is introduced into the transmission tube at a substation, it immediately serves to obstruct the free passage 30 of air through the tube 2. This causes a slight drop in pressure in the chamber 11 as well as in the transmission tube and in tube 47, thus decreasing the pressure in the chamber 44 behind the auxiliary motor 35 diaphragm 41. The diaphragm 41 immediately moves upwardly as viewed in Fig. 2 thereby bringing the uppermost of the shoulders 75 into engagement with the member 76 of the latch 66, raising the valve 40 lever 61 and lifting the regulating valve 60 from its seat. This immediately permits atmospheric pressure to build up in the chamber 24 and as the opposite side of the main motor diaphragm 20 is exposed to the 45 pressure of the vacuum tank, this diaphragm is immediately depressed against the spring 28, thus fully opening the main valve 16 and permitting a large volume of air to rush through the transmission tube 2, thereby moving the carrier along the tube. 50 As the auxiliary diaphragm 41 moves upwardly, the latch member 66 is caused to assume the position shown in Fig. 3 wherein the surface 76 is shown as on the point of becoming disengaged from the surface 75. 55 As soon as the latch is disengaged, the valve 60 closes, thus cutting off communication between the chamber 24 and the outside atmosphere. The air within the chamber 60 24 now bleeds slowly past the needle valve 35 until the pressure in the chamber 24 is reduced sufficiently to permit the spring 28 to restore the diaphragm 20 to its original position. This movement of the diaphragm 65 takes place slowly at first in accordance

with the reduction in pressure in the chamber 24 but as the opening 31 in the valve stem 17 is uncovered during the upward movement of the stem, a passage is afforded between the chamber 24 and the chamber 70 12 which permits the air of the chamber 24 to be exhausted at a much more rapid rate than is possible through the needle valve. This causes the main valve 16 to approach its seat much more rapidly during the final 75 movement of the valve than during the first part of its closing movement so that the valve is caused to act with much greater certainty than is usually the case. It will be noted that the closing of the valve 16 depends upon the setting of the needle valve 80 35 and is entirely independent of the pressure which may prevail in the transmission tube 2, after the controlling operation has once been initiated. In other words the closing of the valve 16 is not dependent upon the reverse movement of the diaphragm 41 but may be caused to occur at a predetermined and definite interval of time after 85 its opening. If the carrier has emerged 90 from the transmission tube 2 prior to the closing of the valve 16 the parts will occupy the position of Fig. 2, as the spring 58 restores the diaphragm 41 to its normal position as soon as the pressure in the tube 6 95 rises to or above normal. During the downward movement of the diaphragm 41 the flanges 71, 72, 73 pass freely by the latch member 66 which turns in opposition to its spring for permitting this movement, the 100 latch immediately snapping successively behind the several flanges as the parts approach normal position. If, however, the carrier has not emerged from the tube 2 when the valve 16 closes, the pressure in the 105 chamber 11 may not rise fully to normal, in which case the shoulder 76 of the latch may only snap over the lowermost or the intermediate shoulder 75 and if the carrier slows down the resultant decrease in pressure in 110 the tube immediately again lifts diaphragm 41, opening valve 60 part way and thus allowing valve 14 to open partially. A new impulse is thus imparted to the carrier, but this new impulse need not be as energetic as the original one since the carrier is already moving. Thus by a series of timed impulses the carrier may be moved to its destination with the expenditure of 115 a minimum amount of air. If while the first carrier is in the tube, a second carrier should be introduced, the main valve 16 is not necessarily opened, as the opening of the valve is only occasioned by a drop in 120 pressure in the transmission tube occurring when the latch 66 is engaged with the stem 54. The tube 47 which connects the tube 6 with the chamber 44 is provided with the bent end 48 so that this tube constitutes an impact tube which serves to transmit very 125 130

small pressure variations in the tube 6 to the chamber 44. With this arrangement the slightest increase in pressure in the air current flowing in the tube 6 is immediately felt in the chamber 44 so that the diaphragm 41 is highly responsive to increase in pressure and is quickly restored to position wherein it is operatively engaged with the regulating valve 60. By providing a series of the flanges 71 etc. upon the stem 54 the diaphragm 41 may pick up the valve 60 for further operation even though the diaphragm may not previously have been restored fully to its normal position, as above described.

The device shown in Fig. 4 provides but a single flange 71^a for engagement with the latch and under some circumstances this may be found sufficient, it being preferred however to employ a plurality of the flanges for the reasons previously pointed out. The controlling apparatus thus devised is of very compact form and requires relatively few parts in its construction. The parts are nearly all contained within the casing or housing so that they are not exposed to accidental injury and the apparatus is readily capable of installation in the restricted spaces commonly available for such purposes.

What we claim and desire to secure by Letters Patent of the United States is:

1. In combination in a pneumatic dispatch system, a carrier transmission tube, means for causing a current of air of normal predetermined amount constantly to enter the mouth of the tube, and controlling means, comprising a pressure actuated element constantly exposed upon one side to the pressure in the transmission tube and freely open upon the other side to the atmospheric pressure, for admitting an abnormal quantity of air to flow through the tube for a predetermined interval of time.

2. In combination in a pneumatic dispatch system, a carrier transmission tube through which a current of air of normal substantially predetermined amount flows constantly, and means operative by variation in pressure in the tube due to the introduction of a carrier therein for permitting an abnormal quantity of air to flow through the tube for a predetermined interval independent of the presence of a carrier in the tube, said means including a diaphragm constantly exposed on one side to full atmospheric pressure.

3. Apparatus of the class described comprising a transmission tube for carriers, and means operative upon decrease in pressure in said tube due to the presence of a carrier therein for admitting a large volume of air to flow through the tube for a predetermined length of time, and thereafter to admit air in relatively smaller volume upon

subsequent decrease in pressure in the tube due to the continued presence of the carrier therein.

4. Apparatus of the class described comprising a normally open transmission tube for carriers, and automatic means for subjecting a carrier within the tube to a plurality of impulses of predetermined duration comprising a pressure actuated diaphragm constantly exposed upon one side to the pressure of the transmission tube and freely exposed upon the other side to atmospheric pressure.

5. Apparatus of the class described comprising a normally open transmission tube, a suction tube, valve means normally substantially closing communication between said tubes, and means actuated by pressure variation in the transmission tube due to introduction of a carrier therein for initiating opening of the valve means to determine closing thereof after a predetermined interval independent of the continued presence of the carrier in the tube, said means comprising a diaphragm constantly exposed on one side to atmospheric pressure.

6. Apparatus of the class described comprising a transmission tube, a suction tube, a spring pressed valve normally closing a passage between said tubes, a pneumatic motor for opening said valve, an auxiliary motor actuatable by introduction of a carrier within the transmission tube, means normally connecting said motors for initiating operation of said first motor upon actuation of the auxiliary motor, and means automatically disconnecting said motors after said first motor begins to operate.

7. Apparatus of the class described comprising a transmission tube and a suction tube, a valve for controlling a passage between said tubes, a pneumatic motor comprising a diaphragm for moving said valve, a device movable in response to fluctuation in air pressure in the transmission tube due to introduction of a carrier therein, and connections actuatable by said movable device for determining admission of pressure fluid to one side of said diaphragm, said connections comprising automatically disengageable parts.

8. Apparatus of the class described comprising a transmission tube and a suction tube, a valve for controlling a passage between said tubes, a spring normally operative to move said valve in one direction, a pneumatic motor for moving the valve in the opposite direction, a regulating valve for determining operation of the motor, a movable element responsive to fluctuation in air pressure in the transmission tube, and connections between said element and said last named valve, said connections comprising disengageable parts constructed and arranged automatically to separate after a

predetermined operative movement of said movable element.

9. Apparatus of the class described comprising a transmission tube and a suction tube, a main valve for controlling a passage between said tubes, a spring normally operative to move said valve in one direction, a main pneumatic motor comprising a diaphragm for moving the valve in opposition to its spring, an auxiliary motor having a diaphragm sensitively responsive to fluctuation in air pressure in the transmission tube, a regulating valve for determining the admission of pressure fluid to one side of the diaphragm of said first motor, and connections between said regulating valve and the diaphragm of the auxiliary motor, said connection comprising a latch pivoted to one of said parts and normally 10 engaging an element moving with the other of said parts.

10. Apparatus of the class described comprising a transmission tube and a suction tube, a valve for controlling a passage 25 between said tubes, a spring normally operative to move said valve in one direction, a motor for moving the valve in opposition to its spring, a movable member for determining initiation of operation of said 30 motor, a pressure actuated part sensitively responsive to variation in pressure in the transmission tube by introduction of a carrier therein, a latch lever pivotally mounted upon the movable member, and a latch engaging abutment moving with said pressure actuated part whereby movement of the latter serves to actuate said movable member.

11. Apparatus of the class described comprising a transmission tube and a suction tube, a main valve for controlling a passage 40 between said tubes, a spring normally operative to move said valve in one direction, a fluid motor for moving the valve in opposition to its spring, a pivotally supported 45 regulating valve for the motor, a part sensitively responsive to decrease in air pressure in the transmission tube, a latch carried by said regulating valve, and a part having a latch engaging abutment shoulder 50 associated and moving with said sensitively responsive part, said latch and shoulder being constructed and arranged automatically to become disengaged after a predetermined movement of said sensitively responsive 55 part.

12. Apparatus of the class described comprising a transmission tube and a suction tube, a main valve for controlling a passage 60 between said tubes, a spring normally operative to move said valve in one direction, a pneumatic motor for moving the valve in opposition to its spring, a pivotally supported regulating valve for determining 65 actuation of the motor, an auxiliary motor comprising a diaphragm responsive to

fluctuation in pressure in the transmission tube by reason of introduction of a carrier therein, a stem secured to said diaphragm having a radial shoulder projecting therefrom, and a latch carried by the regulating 70 valve and engageable with said shoulder for transmitting movement from the diaphragm to the regulating valve, said latch being constructed and arranged to disengage said shoulder upon a predetermined movement 75 of the diaphragm.

13. Apparatus of the class described comprising a transmission tube and a suction tube, a valve for controlling a passage between said tubes, means normally tending 80 to close said valve, a fluid motor for opening the valve, a regulating valve for the fluid motor, a diaphragm responsive to fluctuation in pressure in the transmission tube, a stem carried thereby, said stem having a head of truncated pyramidal form 85 providing a radial shoulder at its base, and a latch carried by said regulating valve and automatically engageable with said shoulder upon movement of the diaphragm in one 90 direction, and automatically disengageable from said shoulder after a predetermined extent of movement of the diaphragm in the opposite direction.

14. Apparatus of the class described comprising a transmission tube and a suction tube, a main valve for controlling a passage between said tubes, means normally tending to close said valve, a fluid motor for opening the valve, a regulating valve for the fluid 95 motor, a diaphragm responsive to fluctuation in pressure in the transmission tube, a stem carried thereby, said stem having a plurality of axially spaced shoulders outstanding therefrom, and a latch pivotally 100 secured to said regulating valve and engageable with either of said shoulders whereby to transmit movement from the diaphragm 105 to the regulating valve.

15. Apparatus of the class described comprising a transmission tube and a suction tube, a main valve for controlling a passage between said tubes, means normally tending to close said valve, a fluid motor for opening the valve, a regulating valve for the fluid 110 motor, a diaphragm responsive to fluctuation in pressure in the transmission tube, a stem carried thereby, said stem having an enlarged head of truncated pyramidal form 115 providing an inclined peripheral surface and a radial shoulder, a latch pivotally supported upon the regulating valve, and means for limiting swinging of the latch about its pivot, said latch being constructed and arranged to engage said radial shoulder 120 upon movement of the stem in one direction, and to be disengaged therefrom by a movement of the regulating valve of a predetermined extent.

16. Apparatus of the class described com- 125

- prising a transmission tube and a suction tube, a main valve for controlling a passage between said tubes, means normally tending to close said valve, a fluid motor for opening 5 the valve, a regulating valve for the fluid motor, a diaphragm responsive to fluctuation in pressure in the transmission tube, a stem carried thereby, said stem having a series of truncated, pyramidal flanges providing spaced radial shoulders, and a latch member carried by the regulating valve and engageable with either of said shoulders for transmitting movement from the diaphragm to the regulating valve.
- 10 15 17. Apparatus of the class described comprising a transmission tube, a suction tube, and a valve for controlling a passage between said tubes, fluid motor means for opening said valve, a diaphragm responsive to fluctuations in pressure in the transmission tube, a regulating valve for determining the operation of said motor, means movable with the diaphragm in one direction for opening said regulating valve, and means 20 25 operative independently of the diaphragm for closing said latter valve.
18. Apparatus of the class described comprising a transmission tube, a suction tube, and a valve for controlling a passage between said tubes, fluid motor means for opening said valve, a diaphragm responsive to fluctuations in pressure in the transmission tube, a valve for regulating the operation of said motor means, automatically disengageable connections for transmitting movement to the regulating valve from the diaphragm during movement of the latter in one direction only, and independent means for moving the regulating valve in the opposite direction.
- 30 35 40 45 50 55 60 65 70 75 80 85 90 95 100 105 110 115 120 125 130 135
19. Apparatus of the class described comprising a transmission tube, a suction tube, and a valve for controlling a passage between said tubes, a fluid motor for opening said valve, a diaphragm responsive to fluctuations in pressure in the transmission tube, a regulating valve for determining the operation of said motor, means for moving the regulating valve with the diaphragm as the latter moves in one direction, said means automatically becoming inoperative after a predetermined extent of movement, and spring means for restoring the regulating valve to initial position.
20. Apparatus of the class described comprising a transmission tube, a suction tube, a valve for controlling a passage between said tubes, and automatic means for opening and closing said valve, said means being constructed and arranged to increase the speed of said movement of the valve as it nears the end of its closing movement.
21. Apparatus of the class described comprising a transmission tube, a suction tube, and an opening providing communication

therebetween, said opening being defined by an annular valve seat, a valve co-operating with said seat, a spring normally tending to close the valve, a fluid motor for opening the valve and for permitting it to close under action of the spring, and means for permitting the valve to move more rapidly as it nears its seat in closing than during the earlier part of its closing movement.

22. Apparatus of the class described comprising a transmission tube, a suction tube and a valve for controlling a passage therebetween, a diaphragm exposed upon its front side to the pressure in the suction tube, means connecting the diaphragm and valve, a spring normally tending to close the valve, and means operative suddenly to relieve pressure upon the rear side of the diaphragm during the closing of the valve to permit the valve to complete its closing movement rapidly.

23. Apparatus of the class described comprising a transmission tube, a suction tube and a valve for controlling communication therebetween, a diaphragm exposed upon its front side to the pressure in the suction tube, a stem connecting the diaphragm and valve, a spring surrounding said stem and normally tending to close the valve, means for admitting pressure fluid to the rear side of the diaphragm for opening the valve, means for exhausting such pressure fluid at a predetermined rate to permit the valve to close, and means permitting such pressure fluid to exhaust at a greater rate as the valve approaches its closed position.

24. Apparatus of the class described comprising a transmission tube, a suction tube and a valve for controlling a passage therebetween, a diaphragm exposed upon its front side to the pressure in the suction tube, means connecting the diaphragm and valve, a spring normally tending to close the valve, means admitting pressure fluid to the rear side of the diaphragm for opening the valve and for exhausting such pressure fluid at a predetermined rate to permit the valve to close, and a passage for permitting such pressure fluid to exhaust at a greater rate during the final portion of the closing movement of the valve.

25. Apparatus of the class described comprising a transmission tube, a suction tube and a valve for controlling a passage therebetween, a diaphragm exposed upon its front side to the pressure in the suction tube, a stem connecting the diaphragm and valve, said stem having an axially extending passage opening at one end at the rear side of the diaphragm and at the other at a point in the side of the stem at the front of the diaphragm, a spring surrounding the stem and normally tending to close the valve; and means for admitting pressure fluid to the rear side of the diaphragm and

- for permitting it to exhaust therefrom at a predetermined rate, said axially extending passage in the stem being constructed and arranged suddenly to increase the rate of 5 exhaust of such pressure fluid as the valve nears its closed position.
26. Apparatus of the class described comprising a transmission tube, a suction tube, and a valve for controlling a passage there- 10 between, a diaphragm exposed upon its front side to the pressure in the suction tube, a stem connecting the diaphragm and valve, a fixed sleeve forming a guide for said stem, said stem having an axially ex- 15 tending passage opening at one end at the rear side of the diaphragm and at the other end at a point in the side of the stem, a spring normally tending to close the valve, and means for admitting pressure fluid to 20 the rear of the diaphragm for opening the valve and for permitting such fluid to exhaust at a predetermined rate to allow the valve to close, said sleeve closing the opening of said passage at the side of the stem 25 when the valve is fully open but exposing such opening as the valve approaches its closed position.
27. Apparatus of the class described comprising a transmission tube, a suction tube 30 and a valve for controlling a passage there- between, and a fluid motor for determining operative movement of said valve, said motor comprising a diaphragm responsive to slight variations in air pressure, and a tube 35 projecting into the transmission tube and having its end directed oppositely to the flow of air therein, the other end of the tube communicating with the space to one side of the diaphragm.
- 40 28. Apparatus of the class described comprising a transmission tube, a suction tube and a valve for controlling a passage therebetween, and a fluid motor for determining operative movement of said valve, 45 said motor comprising a movable element responsive to fluctuations in pressure, and an open ended impact tube having one end thereof disposed within the transmission tube and directed oppositely to the flow of 50 air therein, said tube being constructed and arranged to transmit variations in pressure from the transmission tube to said movable element.
- 55 29. Apparatus of the class described comprising a transmission tube, a suction tube and a valve for controlling communication therebetween, and a fluid motor for determining operative movement of said valve, 60 said motor comprising a casing, a dia- phragm within the casing movable in response to variations in air pressure upon its opposite sides, and a tube opening at one end into the space to one side of the dia- phragm and at the other into the transmis- 65 sion tube, the latter end of the tube being disposed at substantially right angles to the main part thereof and being directed oppositely to the flow of air in the transmission tube.
30. Apparatus of the class described comprising a transmission tube and a suction tube, said tubes having horizontally disposed, aligned portions, a casing into which said portions open, said casing having a transverse partition provided with an opening defined by a horizontal annular valve seat, a valve movable upwardly into engagement with said seat, a spring normally tending to close the valve, a diaphragm in the upper part of said casing exposed upon its lower side to the pressure of the suction pipe and connected to the valve, an auxiliary diaphragm arranged within a chamber in said casing, means for transmitting fluctuations in pressure in the transmission tube to said auxiliary diaphragm, and means actuatable by said latter diaphragm for admitting atmospheric pressure to the upper side of said first diaphragm. 70 75 80 85
31. Apparatus of the class described comprising a unitary casing having a chamber communicating with a transmission tube, a second chamber communicating with a suction tube, a valve controlled passage between said chambers, a diaphragm forming one wall of said second chamber and defining a normally closed space at its opposite side, a regulating valve for admitting atmospheric pressure to said space, a third chamber in said casing, a diaphragm forming one wall of said third chamber and constantly exposed upon its outer side to atmospheric pressure, means connecting said latter diaphragm with said regulating valve 90 95 100 105
32. Apparatus of the class described comprising a transmission tube and a suction tube, and a casing having a pair of fluid motors therein, a regulating valve for determining actuation of one of said motors, connections between said other motor and said valve, and a valve for controlling a passage between said tubes, said valve being operatively connected with the first motor. 110 115
33. Apparatus of the class described comprising a casing having an apertured partition across the same, a valve controlling the aperture in the partition, a diaphragm extending across the chamber to one side of the partition, a valve governed aperture in the wall of the casing behind said diaphragm, a second diaphragm parallel to and co-axial with the first diaphragm, means actuatable by the second diaphragm for opening said valve governed aperture, and means connecting said first diaphragm with the valve in the partition. 120 125 130
34. Apparatus of the class described com-

prising a casing having co-axial diaphragms therein, a main valve connected with one diaphragm, a regulating valve for the latter diaphragm actuable by the second diaphragm, and means for transmitting a variable fluid pressure to said second diaphragm.

35. Power transmission apparatus of the class described comprising a casing having 10 co-axial diaphragm chambers, a diaphragm in each chamber, a valve connected to one diaphragm, a regulating valve for determining admission of pressure fluid to one

side of said latter diaphragm, automatically disengageable connections between the said 15 regulating valve and the second diaphragm for transmitting movement to said regulating valve during a predetermined extent only of the movement of said second diaphragm, and means admitting variable fluid 20 pressure to said second diaphragm.

Signed by us at Boston, Massachusetts this fourth day of August 1922.

CHESTER S. JENNINGS.
CLIFFORD R. DUMBLE.
